UNITED STATES PATENT OFFICE

HENRY W. FISCH, OF LOS ANGELES, CALIFORNIA

HYDRAULIC CLEAN-OUT DEVICE

Application filed May 8, 1929. Serial No. 361,391.

This invention relates to a hydraulic clean-out device adapted to be used in cleaning outlets from sinks and the like.

An object of the invention is to provide an improved clean-out device having a handle and a dome-shaped rubber cap thereon adapted to be placed over the drain or outlet from the sink and to provide the device with a spring adapted to engage and be compressed 10 against the strainer over the drain. By the improved construction when the handle is forced downwardly flexing the cap some fluid is forced thereby through the drain. On releasing the handle, however, as some fluid has 15 been forced through the drain the cap will not immediately return to its normal position because of the partial vacuum formed therein. The presence of the spring serves to assist the cap returning to normal position so that the 20 handle may be easily and quickly reciprocated causing the fluid in the drain to be agitated and forced through the drain sufficiently to readily clean the drain.

Another object of the invention is to provide a hydraulic clean-out device for sink drains and the like having a hollow handle and a dome-shaped cap thereon and to provide a construction for conveying fluid such as water under pressure to the interior of the 30 handle to be discharged through the cap into the drain. Other objects of the invention are to provide a check valve in the handle so that reverse flow through the handle is effectively prevented while the cap is being flexed under downward movement of the handle and to provide a convenient construction for forcing the handle downwardly to force the fluid through the sink drain.

With the foregoing and other objects in view which will be made manifest in the following detailed description and specifically pointed out in the appended claims, reference is had to the accompanying drawings where- 45 in,

The figure is a view in vertical section illustrating the improved hydraulic clean-out device in applied position.

Referring to the accompanying drawings wherein similar reference characters designate similar parts throughout, the improved device comprises a hollow handle 10 which may be formed of pipe or the like and which has its upper end closed as indicated at 11. Laterally extending hand grips are provided 55 on the handle one hand grip being indicated at 12 having a closed outer end 13 and having its inner end threadedly connected as at 14 to the handle 10. The other hand grip comprises a short section of pipe indicated at 15 having its 60 inner end threaded into the handle 10 as at 16 and having its outer end open and adapted to receive the coupling member 17 on a hose 18. The hose 18 is adapted to be connected by a coupling member 19 to the water faucet 20. 65

On the lower end of the handle 10 there is secured a hollow dome-shaped cap 21 and within this cap there is disposed a coil spring 22 which is approximately equal in length to the distance from the top of the cap to its 70 bottom. This spring is secured to the under side of the cap adjacent its top. Within the lower end of the handle there is threadedly mounted a valve cage 23 having ports 24 and within the valve cage there is threadedly 75 mounted a valve supporting member 25. The valve supporting member 25 has downwardly convergent ports 26 formed therein which merge into a single port discharging through the top of the rubber cap 21. The valve supporting member 25 has an upwardly extending stem 27 which extends through the cage and a valve closure 28 is slidably thereon adapted to open and close the ports 24. This 80 valve closure constitutes a check valve preventing reverse flow through the handle.

The operation of the improved device is as follows: When the drain D of the sink S becomes clogged the hose 18 is connected to the water faucet 20. The handle 10 is then 90

manipulated so as to position the rubber dome-shaped cap 21 over the strainer S¹ on the drain D. By holding the handle the water can be turned on causing the water to flow through the hose 18, the hand grip 15, the handle 10, pass the check valve and to be discharged through the cap. If the water pressure developed is insufficient to force the obstruction through the drain D the operator may grasp the hand grips 12 and 15 and force the handle downwardly. This flexes the dome-shaped cap 21 and compresses the spring 22. Reverse flow through the handle is prevented by the check valve. Consequently, if the water pressure is insufficient the operator may force the handle downwardly or reciprocate it developing a sufficient pressure or producing sufficient agitation within the drain D to dislodge the obstruction. In some instances the improved device may be used without having the hose 18 connected to the water faucet 20 and when such is the case the check valve 28 prevents reverse flow through the handle 10 when the device is pressed downwardly over the strainer S¹. When the device is so used and fluid is forced from the interior of the cap 21 through the drain the cap will not immediately return to normal position because of the partial vacuum formed in the cap. By virtue of the fact that the coil spring 22 is compressed it assists the dome-shaped cap returning to normal overcoming the effect of the partial vacuum produced therein.

35 From the above described construction it will be appreciated that an improved clean-out device is provided which may be used under circumstances wherein it is desired to connect the device to a water supply or the 40 device may be used dry, that is, without having water discharged through the device.

Various changes may be made in the details of construction without departing from the spirit or scope of the invention as defined 45 by the appended claims.

I claim:

1. A clean-out device for sinks and the like comprising a handle, a dome-shaped resilient cap mounted on the handle adapted to be 50 positioned over a sink, and a spring secured within the cap adapted to engage the sink and return the cap and handle to normal position after the cap has been depressed.

2. A clean-out device comprising a hollow 55 handle, a dome-shaped cap secured to the handle adapted to be positioned over a sink outlet, and means for conveying water pressure to the interior of the handle to be discharged under pressure through the cap, there 60 being a check valve in the entrance to the cap for preventing reverse flow therethrough, and a spring secured within the cap engageable over the sink outlet for assisting in returning the cap and handle to normal position 65 after the cap has been depressed.

3. A clean-out device for sink outlets and the like comprising a hollow handle, a dome-shaped cap mounted on the handle, hand grips mounted on the handle, one of said hand grips being hollow and adapted to 70 convey fluid under pressure to the interior of the handle to be discharged through the cap.

In testimony whereof I have signed my name to this specification.

H. W. FISCH.
